UNITED STATES PATENT OFFICE.

EDWARD DITHRIDGE AND EDWARD D. DITHRIDGE, OF PITTSBURG,
PENNSYLVANIA.

IMPROVED LAMP-CHIMNEY.

Specification forming part of Letters Patent No. 33,428, dated October 8, 1861.

To all whom it may concern:

Be it known that we, EDWARD DITHRIDGE and EDWARD D. DITHRIDGE, of Pittsburgh, in the county of Allegheny and State of Pennsylvania, have invented a new and Improved Chimney for Lamps; and we do hereby declare that the following is a full and exact description thereof, reference being had to the accompanying drawings, and to the letters of reference marked thereon.

The nature of our invention consists in making a lamp-chimney with a round base and top and an oval-shaped bulge for the purpose of adapting it to the ordinary round mounting of lamps in which flat wicks are used, and also for bringing the air equally in contact with the blaze.

To enable others skilled in the art to make and use our invention, we will proceed to describe its construction and operation.

In the accompanying drawings, Figure 1 is a perspective view in outline of the chimney. Fig. 2 is a cut or sectional view and represents the oval shape of the bulge of chimney, and also represents the wick-holder and its relative position to the chimney. Fig. 3 is a cut or sectional view of the bulge of the old and well-known form of chimney for lamps in which flat wicks are used.

a is the chimney.

b is the wick-holder.

c is the space for the wick.

The advantages of our improvement are as follows:

First. The space between the blaze and wick of the lamp and the sides of the chimney being equally divided by means of the oval-shaped bulge, the air is evenly distributed around the wick and blaze. Thus all liability of the chimney becoming smoked is avoided.

Second. The oval shape of the bulge will allow the chimney to expand suddenly without liability of cracking. It will be observed that

the ordinary chimney with the round bulge when suddenly heated is very liable to crack, the expansion having to follow the circle, and glass not being of a pliant nature, it must of necessity crack when suddenly heated. Now the only way to obviate the cracking of the chimney is to make the bulge oval-shaped, which will allow the two flat sides of the bulge to vibrate and thus relieve the chimney from all strain caused by expansion.

Third. The equal distribution and uniform action of the air on the wick and blaze caused by the oval-shaped bulge will give a larger and brighter light than can be obtained by the use of the round bulge in the ordinary chimney.

Fourth. By the use of the round base when used in connection with the oval-shaped bulge all grinding and fitting are avoided, thereby saving greatly in the cost of manufacture.

Fifth. The round base when used in connection with the oval-shaped bulge adapts the chimney to the ordinary round mounting of lamps which are now in general use.

Sixth. The chimney is not liable to be broken by accident caused by rolling. Hence it will not require so much care in handling.

We are aware that lamp-shades have been made of an oval shape having an oval base. Therefore we do not claim, broadly, the use of the oval shape or formed lamp chimney or shades; but

What we do claim is—

A new article of manufacture, consisting of a lamp-chimney with a round base and top and an oval-shaped bulge, arranged and constructed as herein described, for the purpose set forth.

EDWD. DITHRIDGE.
